(57) **CLAIM**

The ornamental design for a steering wheel base for electronic driving simulator systems, as shown and described.

DESCRIPTION

FIG. 1 is a photograph from a front left perspective of a steering wheel base showing the new design.

FIG. 2 is a photograph of the front of the steering wheel base shown in FIG. 1.

FIG. 3 is a photograph from a back left perspective of the steering wheel base shown in FIG. 1.

FIG. 4 is a photograph from a back right perspective of the steering wheel base shown in FIG. 1.

FIG. 5 is a photograph of the back of the steering wheel base shown in FIG. 1.

FIG. 6 is a closeup photograph of a portion of the back of the steering wheel base shown in FIG. 1.

FIG. 7 is a photograph of the left side of the steering wheel base shown in FIG. 1.

FIG. 8 is a photograph of the right side of the steering wheel base shown in FIG. 1.

FIG. 9 is a photograph of the top of the steering wheel base shown in FIG. 1; and,

FIG. 10 is a photograph of the bottom of the steering wheel base shown in FIG. 1.

Features depicted in half-tone shading and surrounded by broken lines show portions of the steering wheel base that form no part of the claimed design.
